DRIVE POINT FOR EXPLOSIVE CHARGE

Stanley T. Graham and Robert G. Rintoul, both of 448
42nd Ave. SE, Calgary 24, Alberta, Canada

Filed June 24, 1969, Ser. No. 17,842

Term of patent 14 years

Int. Cl. D22—03

U.S. Cl. D22—10

FIG. 1 is a perspective view of the drive point for explosive charge, showing our new design;

FIG. 2 is a bottom view of the drive point, and

FIG. 3 is a top view of the drive point.

We claim:

The ornamental design for a drive point for explosive charge, as shown.
